US0D1014188S

(12) **United States Design Patent** (10) **Patent No.:** **US D1,014,188 S**
(45) **Date of Patent:** **** Feb. 13, 2024**

(54) **MIXER DEVICE**

(71) Applicant: **TRRS MAGNATE, LLC**, Manteca, CA (US)

(72) Inventor: **Thomas Anthony Raymus**, Manteca, CA (US)

(73) Assignee: **TRRS MAGNATE, LLC**, Manteca, CA (US)

(**) Term: **15 Years**

(21) Appl. No.: **29/883,891**

(22) Filed: **Feb. 3, 2023**

Related U.S. Application Data

(63) Continuation of application No. 29/883,237, filed on Jan. 25, 2023.

CLAIM

The ornamental design for a mixer device, as shown and described.

DESCRIPTION

FIG. 1 is a perspective view of the mixer device;

FIG. 2 is a first side view thereof;

FIG. 3 is a second side view thereof;

FIG. 4 is a third side view thereof;

FIG. 5 is a fourth side view thereof;

FIG. 6 is a top view thereof;

FIG. 7 is a bottom end view thereof;

FIG. 8 is a perspective view thereof within a water bottle environment; and,

FIG. 9 is a perspective alternate view thereof within a water bottle environment.

The dotted lines depict environment that forms no part of the claimed design.

1 Claim, 9 Drawing Sheets
